(57) **CLAIM**

The ornamental design for a footwear upper, as shown and described.

DESCRIPTION

FIG. 1 is a perspective view of a preferred embodiment of the footwear upper;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines appearing in the pattern of two small lines followed by a long line in FIG. 7 and at the bottom of FIG. 2 are provided only to indicate the boundary of the claimed design. These broken lines and the area lying within them form no part of the claimed design.
